(57) **CLAIM**

The ornamental design for a mounting bracket with ejection mechanism for holding a cylindrical tank, as shown.

DESCRIPTION

FIG. 1 is a front three-quarter perspective view embodying our new design;

FIG. 2 is a front plan view;

FIG. 3 is a side plan view taken from the left of FIG. 2;

FIG. 4 is a side plan view taken from the right of FIG. 2;

FIG. 5 is a rear plan view;

FIG. 6 is a top plan view; and,

FIG. 7 is a bottom plan view.

The broken line showing of a tank is for illustrative purposes only and forms no part of the claimed design.
